WITNESS:

P.G.Wall.

INVENTOR

ATTORNEY

UNITED STATES PATENT OFFICE.

PORTER G. WALL, OF ARARAT, NORTH CAROLINA.

FURNACE DOOR.

Application filed June 12, 1922. Serial No. 567,715.

To all whom it may concern:

Be it known that I, PORTER G. WALL, a citizen of the United States, residing at Ararat, in the county of Surry and State of North Carolina, have invented new and useful Improvements in Furnace Doors, of which the following is a specification.

This invention relates to a door for a furnace used in tobacco barns, the general object of the invention being to provide a sliding door which may be opened to any desired extent to control the draft to the furnace.

This invention also consists in certain other features of construction and in the combination and arrangement of the several parts, to be hereinafter fully described, illustrated in the accompanying drawings and specifically pointed out in the appended claim.

20 In describing my invention in detail, reference will be had to the accompanying drawings wherein like characters denote like or corresponding parts throughout the several views, and in which:—

25 Figure 1 is a fragmentary side view of a furnace with my door thereon.

Figure 2 is a longitudinal sectional view through Figure 1.

30 Figure 3 is a detail view of the latch means with parts in section.

Figure 4 is a fragmentary rear view of the frame.

In these views 1 indicates the furnace and 2 indicates the door frame which is attached 35 to the front end of the frame. This frame consists of the upright pieces 3 which are provided with the grooves 4 to receive the edges of the door 5. Each upright piece is provided with a base 6, the outer end of 40 which is connected with the upright piece by the brace 7. A rod 8 is attached to the top of the frame, said rod being provided with notches 9 for receiving the end of a latch 10 which is carried by a projection 11 45 on the top of the door. This latch is provided with a handle 12 so that it can be moved into and out of engagement with the notches in the rod. By this means the

door can be opened to different degrees so as to regulate the draft passing through the door opening. The door can be entirely closed and the draft will be cut off, thus holding the fire and preventing sparks from escaping from the furnace.

This door will control the heating of the barn by the furnace, will prevent back-firing and acts to hold the fire for a long time without renewal of the fuel when said door is closed.

The rear part of the frame is provided with recesses 3' for holding mortar or the like and the frame is supported by means of the rods 13 which are adapted to be driven into the ground and which pass through holes in the brackets 14 and in the bases 6. A cotter pin 15 or the like passes through each rod and engages the under face of each bracket 14 so as to form a rest on the rod for the frame.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A door for a furnace comprising a frame having openings in its rear for receiving binding means for connecting it with the front of a furnace, said frame having guideways therein, a slide vertically movable in the guideways, latch means for holding the slide in adjusted position, a base member at each side of the frame having a hole therein, a bracket at each side of the frame adjacent the upper end thereof, a rod passing through the bracket and the hole in each base member and adapted to have its end enter the ground to hold the frame in position and a projection on each rod for forming a rest for each bracket.

In testimony whereof I affix my signature.

PORTER G. WALL.
